UNITED STATES PATENT OFFICE.

MEYNARDIE NELSON, OF LITTLETON, NORTH CAROLINA.

PAPER-CUTTER.

1,116,834.

Specification of Letters Patent.

Patented Nov. 10, 1914.

Application filed October 18, 1913. Serial No. 795,826.

To all whom it may concern:

Be it known that I, MEYNARDIE NELSON, a citizen of the United States, and resident of Littleton, in the county of Halifax and State of North Carolina, have invented certain new and useful Improvements in Paper-Cutters, of which the following is a specification.

This invention relates to paper cutters such as are adapted to be used in stores, for carrying rolls of wrapping paper and cutting the desired lengths of paper from the rolls.

My invention has particular relation to vertical paper cutters of the class just mentioned, and it consists in certain improvements in the cutter of the particular type shown in my previous Patent No. 908,313, dated December 29, 1908.

The object of my present improvements is to provide a cutter of the type indicated, which will possess advantages in point of strength, convenience and ease in assembling the parts, and which will be more accurate and efficient in operation, substantially as hereinafter fully set forth.

In the drawings—Figure 1 is a perspective view of the cutter embodying my present improvements. Fig. 2 is a vertical sectional view of the device. Fig. 3 is a horizontal sectional view, taken on the line $\alpha-\alpha$, Fig. 2. Fig. 4 is a detail vertical sectional view, taken through the connection between the standard and the stationary base. Fig. 5 is a detail vertical sectional view, taken through the connection between the revolving base and the stationary base. Fig. 6 is a detail horizontal sectional view, taken through the knife or cutting blade and showing the connection therewith of one of the arms which carries the blade. Fig. 7 is a detail perspective view, illustrating the recessed edge of the cutting blade and the end of the arm which is received thereby.

Corresponding parts in all the figures are denoted by the same reference characters.

Referring to the drawings, 1 designates a horizontal base, which supports the entire mechanism of the device and is stationary when in use. The under side of this base is hollowed out, as at 2, and the base is provided, at its rear portion, with an upwardly-projecting tubular arm or stud, 3, the bore of which, 4, extends entirely through from top to bottom. This arm 3 is in true upright or vertical position with

relation to the horizontal plane of the base 1, and it is provided in its top edge, at diametrically opposite sides, with recesses, as at 5—5, extending through the walls of the tubular arm or stud and preferably of curved or segmental contour.

6 designates a standard, which rises from the base 1 and carries the knife or cutting blade mechanism and the means for retaining the roll of paper at the top. Said standard is preferably in the form of a rod and of cylindrical contour, and it is detachably connected with the base 1. The lower end, 7, of said standard corresponds to and is received by the bore 4 of the tubular arm 3, and it projects within the hollow space 2 at the under side of the base 1, said projecting terminal bottom end being threaded, as at 8, and adapted to receive a shallow nut, 9, which is screwed up against the under side of the base 1. Immediately above its end portion 7, the standard is provided with laterally-projecting pins or studs, 10—10, respectively at diametrically opposite sides, which are adapted to be received by the respective recesses 5—5 in the top edge of the tubular arm or stud 3. Thus, the nut 9 operates to clamp the pins 10 of the standard in the recesses 5 of the arm 3, and the associate construction affords a secure and accurate detachable connection of the standard with the base 1. The pins 10 are preferably formed by a rod passing transversely through the standard, and they are preferably of cylindrical contour conforming to the contour of the recesses 5.

The paper cutter of the type to which my improvements relate is shipped for transportation in knock-down form, and for this reason the connection of the standard with the base 1 is not only detachable but is designed to be readily and conveniently operable in assembling the device in position for service. The connection as shown in my previous patent above referred to, in which the standard has a threaded end screwed into a threaded opening in the base, is disadvantageous, as it necessitates the turning of the entire standard, and other forms of connection have been found imperfect, as they not only entail considerable difficulty in setting up the device but also do not positively insure the accurate and true vertical position of the standard. It is necessary, in the effective operation of this type of verti-

cal paper cutters, that the standard be in accurate or true vertical or perpendicular relation to the horizontal plane of the stationary base 1, and in the previous methods 5 of attaching the standard to the base the conditions permitted sufficient play to throw the operative parts of the device out of true position, especially in sizes adapted for a heavy roll of paper, weighing, for instance, 10 30 lbs. In the improved construction as comprised in my present invention, the detachable connection between the standard and base effects not only an absolutely true position of the standard, by reason of the 15 seating of the lateral pins 10—10 in the recesses 5—5 of the tubular arm or stud 3, but it also greatly simplifies the operation of assembling the device. In this connection, it is simply necessary, in setting up the 20 device in absolutely true position and ready for service, to insert the lower end of the standard in the tubular arm 3 until the lateral pins 10—10 are seated in the recesses 5—5 at diametrically opposite sides, and 25 then screw home the nut 9 to securely retain the parts in relative position. The improved construction, for attachment of the standard to the base, also enables the shipping of the device for transportation in only 30 two knock-down pieces, one consisting of the stationary base with the revolving base which it carries, and the other consisting of the standard with the arms and cutting blade carried thereby.

35 The stationary base carries a revolving base, 11, mounted substantially in the manner shown in my previous patent, the mounting being preferably of ball-bearing construction. As shown, the stationary base 1 40 has an upwardly-projecting stud, 12, located the required distance from the standard 6 and forming a race channel, 14, for the balls, 15, and the revolving base 11 is centrally provided on its under side with a 45 bearing surface, 16, resting upon the balls. The revolving base also has an upwardly-projecting stud, 17, at the axis of the bearing, and the two bases 1 and 11 are connected in permanent relationship by a headed 50 pin, 18, passing downwardly through bores or perforations, 19—20, in the respective 55 studs 12 and 17 of the bases and having its lower end bradded, as at 21, against the under side of the stationary base 1. This 60 permanent connection between the bases effectively retains the balls 15 and the operative relationship of the bases in transportation.

The revolving base 11 is of circular con- 65 tour, conforming to the contour of the roll of paper, and in my present improvements said base is provided at its circumferential edge or periphery with lateral extensions, 22—22, which enlarge the operative area of 70 the base without increasing its diameter and

75 prevent loose rolls of low grade paper from slipping down at the sides of the base. This improved construction enables the employment of a revolving base of proper size with 80 relation to the stationary base and with respect to the position of the standard 6, such size being in diameter materially smaller than the stationary base, and at the same time provides for effective operation with 85 loose rolls of paper which would exceed the normal diameter or transverse area of the revolving base. The lateral extensions or lips 22—22 are preferably arranged at diametrically opposite sides of the revolving base, as shown. This improved feature of 90 the revolving base, in the application of the device for employment of loose rolls of low grade paper, avoids the necessity of enlarging the entire transverse area of the base and also avoids the enlargement of the dimensions between the projecting stud of the 95 base and the holding pin for the roll of paper at the top, which enlargement would be otherwise necessary to enable the placing of the roll of paper in position in the cutter, 100 as the roll must be tilted when being placed in position. The improved construction whereby the revolving base is of less diametrical dimension than the width of the roll of paper also affords manifest advantages in the operative service of the device with rolls of paper of any quality, whether the paper is of fine grade and not liable to slip down at the sides of the revolving base or whether the paper is of low grade and is 105 therefore liable to work loose and would slip down at the sides of the base unless the extension lips 22 were provided.

110 It will be understood that the roll of paper, as shown at 23, rests upon the revolving base 11 and is carried thereby, with the stud 17 of the base projecting upwardly within the lower end of the central bore of the roll, and that the roll is retained at its top by a pin, 24, projecting within the top 115 end of the bore of the roll and insertibly mounted in a cylindrical socket, 25, at the outer end of an extension, 26, which projects horizontally from the main vertical portion of the standard 6 and at right angles thereto.

120 The cutting mechanism is carried by the standard 6, and comprises arms, 27—27, preferably two in number, which have a terminal eye, as at 28, surrounding the standard 6 and forming a bearing thereon for the arm. The arms 27 are preferably in strip form and carry at their outer ends the knife or cutting blade, 29. Said arms are supported in position, and their operation to 125 cause the cutting blade to bear against the circumference of the roll of paper is governed by coiled springs, 30, which surround the standard 6 and have one end permanently attached thereto, as at 31, and their 130

other free end projecting from the standard and bent at an angle to embrace the side of the arm 27, as at 32, and project over the edge thereof, as at 33.

5 In the improved construction as comprised in my present invention, the sustaining and governing springs 30—30 are reversely arranged with relation to the arms 27—27, that is, the spring for the lower arm is 10 mounted beneath the arm and its retaining end 33 projects at the top edge thereof, while the spring for the upper arm is arranged above the arm and its retaining end 33 projects at the lower edge of the arm. This 15 reversed arrangement of the retaining springs, with relation to the arms carrying the cutting means, as comprised in my present improvements, effectively prevents spreading of the arms from their proper parallel 20 relationship and securely retains the same in true position, and it thus also effectively obviates any binding of the bearing 28 of the arms upon the standard 6 which would result if the arms should spread from their 25 true position in parallel relationship and at right angles to the vertical standard 6.

It is desirable, in the type of vertical paper cutters to which my present invention relates, to employ a fine and thin blade for 30 service as the knife or cutter. Heretofore, the blade has been formed of a plate of non-resilient metal having a sharpened edge, as shown in my previous patent above mentioned. In my present improvements, the 35 cutting blade, as shown at 29, is constituted by a thin sheet of resilient metal, and to prevent bending of this fine thin blade in the knock-down transportation of the device, it is provided with a longitudinal groove or 40 depression, as at 34, forming a projection or rib and preferably formed by stamping the thin metal sheet, said strengthening groove or rib being preferably at approximately the center of the transverse width of the blade. 45 To further strengthen the thin blade, and obviate bending, its rear edge is curved or turned at an angle to its face, as at 35, which curved edge serves as a strengthening rib in substantially the same manner as the groove 50 and rib 34, and in the preferred construction this curved edge 35 is turned in a direction opposite from the direction in which the rib 34 projects. The construction as just described enables the employment of a cutting blade of high resiliency and with the necessary "give" in operation, without liability to bending or damage in transportation. The curved rear edge 35 also enables the effective attachment of the carrying and 55 sustaining arms 27—27, to sustain the blade for resilient action in the cutting operation, and for this purpose this edge is recessed or cut out, as at 36—36, to receive the corresponding end portion, 37, of the arm 27, 60 which latter shoulders or abuts against the

base of the recess, as at 38, and beyond said shoulder the end of the arm is extended, as at 39, to rest against the face of the blade beyond the curved rear edge 35. This improved construction enables the securing of 70 the arm to the blade with a single rivet or brad, as at 40, extending through the extension 39 of the arm and the blade, this single fastening means being merely to secure the blade in connection with the arm while the snug 75 fit and embracing of the end portion of the arm within the recess 36 prevents any tendency of the blade to sag and serves to maintain the blade in absolutely true operative position. 80

The operation of the device, and the advantages of my present improvements, will be readily understood from the foregoing description.

The improved features of construction not 85 only enhance the strength of the various parts, and the convenience and facility with which the device may be shipped in knock-down form and assembled in position for use, but also secure that accuracy of position 90 which is essential in a vertical or perpendicular paper cutter of the type to which my invention relates.

I do not desire to be understood as limiting myself to the detail construction and arrangement of parts as herein shown and described, as it is manifest that variations and modifications therein may be resorted to, in the adaptation of my invention to varying conditions of use, without departing 95 from the spirit and scope of my invention and improvements. I therefore reserve the right to all such variations and modifications as properly fall within the scope of my invention and the terms of the following 100 claims.

Having thus described my invention, I claim and desire to secure by Letters Patent:

1. In a vertical paper cutter of the class described, comprising a stationary base carrying a revolving base for sustaining the roll of paper and a standard projecting from the stationary base and carrying the cutting means operative with relation to said roll, a stationary base having an upwardly-projecting tubular arm or stud provided in its top edge with recesses, a standard having laterally projecting pins or studs, the lower end of the standard being received within said tubular arm and said 110 pins or studs being seated in said edge recesses, and means for fastening said standard in connection with said base to clamp the pins or studs in said edge recesses. 120

2. In a vertical paper cutter of the class 125 described, comprising a stationary base carrying a revolving base for sustaining the roll of paper and a standard projecting from the stationary base and carrying the cutting means operative with relation to 130

said roll, a stationary base having an upwardly-projecting tubular arm or stud provided in its top edge with recesses, a standard having laterally projecting pins or studs, the lower end of the standard projecting through said tubular arm and said pins or studs being seated in said edge recesses, and means upon the lower terminal end of the standard for detachably fastening the same in connection with said base to clamp the pins or studs in said edge recesses.

3. In a vertical paper cutter of the class described, comprising a stationary base carrying a revolving base for sustaining the roll of paper and a standard projecting from the stationary base and carrying the cutting means operative with relation to said roll, a plurality of horizontal parallel arms for carrying the cutting knife or blade and respectively loosely mounted with a bearing upon the vertical standard, and springs carried by the standard and respectively supporting said arms in their horizontal operative position, said springs being reversely arranged with relation to the plurality of arms so that the retaining portions of the different springs operate in reverse directions upon said independently-mounted horizontal arms, whereby the plurality of arms are prevented from spreading from parallel relationship and binding of the arms upon the standard is obviated.

4. In a vertical paper cutter of the class described, comprising a stationary base carrying a revolving base for sustaining the roll of paper and a standard projecting from the stationary base and carrying the cutting means operative with relation to said roll, a pair of horizontal parallel arms for carrying the cutting knife or blade and respectively loosely mounted with bearings upon the standard, and springs for sustaining and retaining the arms in their horizontal position and governing the operation thereof, said springs being carried by the standard and having a projecting portion for retaining the arms, the spring for the lower arm being mounted beneath the arm and supporting the same and having its retaining portion projecting over the top edge thereof and the spring for the upper arm being mounted above the arm and having its retaining portion projecting beneath the lower edge thereof and operatively sustaining the same, whereby the springs are reversely arranged with relation to said independently mounted arms and prevent spreading of the arms from parallel relationship and binding of the arms upon the standard is obviated.

5. In a vertical paper cutter of the class

described, comprising a stationary base carrying a revolving base for sustaining the roll of paper and a standard projecting from the stationary base and carrying the cutting means operative with relation to said roll, a cutting knife or blade constituted by a thin sheet of resilient metal and having its rear edge curved or turned at an angle to its face and provided with recesses, and carrying arms having a bearing upon the standard, the end of said arms corresponding to and fitting in said recesses and being provided with an extension secured to the face of the resilient blade beyond said rear edge thereof.

6. In a vertical paper cutter of the class described, comprising a stationary base carrying a revolving base for sustaining the roll of paper and a standard projecting from the stationary base and carrying the cutting means operative with relation to said roll, a cutting knife or blade constituted by a thin sheet of resilient metal and provided with a longitudinal groove or depression forming a projection or rib beyond its cutting portion and adjacent its rear fastening edge, said rear fastening edge-portion beyond said rib being curved or turned at an angle to the outer face portion of the blade and projecting in a direction opposite from the direction in which said longitudinal rib projects, and carrying arms having a bearing upon the standard and connected with said rear edge of the blade immediately beyond said rib.

7. In a vertical paper cutter of the class described, comprising a stationary base carrying a revolving base for sustaining the roll of paper and a standard projecting from the stationary base and carrying the cutting means operative with relation to said roll, a cutting knife or blade constituted by a thin sheet of resilient metal and provided with a longitudinal groove or depression forming a projection or rib in the rear portion of the body of the resilient metallic sheet beyond its cutting portion and adjacent its rear fastening edge, said rear fastening edge-portion beyond said longitudinal rib being curved or turned at an angle to the outer face portion of the blade, and spring-controlled supporting arms having a bearing upon the standard and connected with said turned rear edge of the blade immediately beyond said rib.

In testimony whereof I have signed my name in the presence of the subscribing witnesses.

MEYNARDIE NELSON.
